(57) **CLAIM**

The ornamental design for a transport box, as shown and
described.

DESCRIPTION

FIG. 1 is a front, perspective view of a transport box in
accordance with the present invention;

FIG. 2 is a rear, perspective view of the transport box shown
in FIG. 1;

FIG. 3 is a right side, perspective view of the transport box
shown in FIG. 1 with the left side being a mirror image
thereof;

FIG. 4 is a front, perspective view of the transport box
shown in FIG. 1 with the portion of the top in an open
position;

FIG. 5 is a top, perspective view of the transport box shown
in FIG. 4;

FIG. 6 is a front, perspective view of another embodiment of
the transport box of the present invention;

FIG. 7 is a front, perspective view of another embodiment of
the transport box of the present invention;

FIG. 8 is a front, perspective view of another embodiment of
the transport box of the present invention;

FIG. 9 is a front, perspective view of another embodiment of
the transport box of the present invention; and,

FIG. 10 is a front, perspective view of another embodiment
of the transport box of the present invention.
